WIRE COILING MACHINE

Albert M. Olgay, Elmwood Park, Ill., assignor to
 The Lakeside Central Company, Chicago, Ill.,
 a corporation of Illinois

Application April 7, 1937, Serial No. 135,422

23 Claims. (Cl. 153—65)

The present invention relates to coil forming machines, and more particularly to such machines wherein the operations thereof are automatically controlled.

5 Among the objects of the present invention is to provide a novel coil forming machine adapted to successively and continuously form coils of the desired length and wherein the various operations for forming such coils are automatically controlled.

10 The present invention comprehends the idea of providing control means in a coil forming machine for successively and continuously forming desired lengths of coil without manual manipulation.

15 Another object within the purview of the present invention is to provide a novel control circuit having means therein for controlling the feeding of the wire forming the coils, the cutting 20 or severing of the coils as formed, and the operation of the coil receiving means for discharging the same from the machine. The invention also includes as an object the idea of providing one or 25 more of these control means, such control means operating independently or in combination with one another.

A still further object of the present invention is to provide in a control circuit for the coil forming machine suitable means whereby the cutting 30 means for the coil is operated only after a predetermined time has elapsed after the feeding means for the wire has become inoperative.

35 Other objects, features, capabilities and advantages are comprehended by the invention, as will later appear and as are inherently possessed thereby.

Referring to the drawings:

Figure 1 is a top plan view of a coil forming machine embodying the present invention;

40 Figure 2 is a view in side elevation of the coil forming machine shown in Figure 1 of the drawings;

45 Figure 3 is a fragmentary view partly in elevation and partly in section taken in the plane represented by line 3—3 of Figure 1 of the drawings;

50 Figure 4 is a view in cross section taken in the plane represented by line 4—4 of Figure 1 of the drawings;

55 Figure 5 is a fragmentary view partly in cross section and partly in elevation taken in the plane represented by line 5—5 of Figure 1 of the drawings; and

55 Figure 6 is a diagrammatic showing of a control

circuit as embodied in the coil forming machine shown in Figure 1 of the drawings.

Referring now more in detail to the drawings, a coil forming machine generally designated as 2 corresponds essentially in the general construction thereof to the coil forming machine disclosed in the Olgay Patent No. 2,089,036, granted August 3rd, 1937, such machine comprising a base 4, having upstanding walls 6 and 8 for supporting a gear train, generally represented as 10 and operated by means of a pulley 12 from any desired source of power. Operated by the gear train 10 are opposite pairs of wire gripping rolls 12 and 14 and 16 and 18, these rolls gripping the wire 20 as the same is fed through guides 22, 24 and 26 15 for feeding the same to coil forming means 28. This coil forming means comprises a spindle 30 about which the wire is coiled by means of the angularly disposed abutments 32 and 34 which may be adjusted as by means of the thumb screws 20 36 and 38, respectively. The pitch for the coil formed on the spindle 30 is controlled by the pitch control member 40 pivotally mounted on the front wall 6 of the base as at 42 and adjusted by means of the mechanism 44, all as clearly disclosed in 25 said Patent No. 2,089,036.

The present invention is directed particularly to control mechanism for the coil forming machine as described above, although it is to be understood that the control mechanism may be 30 used in other coil forming machines if desired. Such control mechanism includes means whereby the machine will automatically operate continuously 35 to form desired lengths of coil, to cut the same into such desired lengths and to discharge these cut lengths of coil from the machine without manual manipulation.

In order to effect these results, the mounting for the upper wire gripping rolls 14 and 18 includes the movable wall section 46 which is engaged by a roller 48 mounted upon a lever 50, one end of which is pivotally connected as at 52 to the opposite walls 6 and 8 of the machine and the other end of which is connected by a rod 54 to the movable core of the solenoid 56 which is 45 mounted for convenience on plate 58 attached to the machine in any desired manner. Upon energizing of the solenoid 56, the outer end of lever 50 is moved downwardly to apply pressure through the roll 48 to the wall section 46 where- 50 by rolls 14 and 18 are moved into gripping engagement with the wire 20 to feed the same onto the spindle 30. The control circuit for the sole- 55 noid 56 will be hereinafter set forth in detail.

Disposed in front of the wall 6 of the coil

forming machine is a coil receiving means 60 which is positioned to receive the coil 62 as the same is formed on the spindle 30. This coil receiving means comprises a frame member 69 to 5 which is secured a bracket 65, this frame member being pivotally mounted as at 7 to the base 4 whereby the coil receiving means may be swung to the right, as viewed in Figure 1 of the drawings, whenever it is desired to inspect the spindle 10 30 or any other element in the immediate vicinity thereof. The coil receiving means is further provided with an elongated abutment 64 disposed at an angle to the vertical and forming, with a corresponding member 66, a substantially V-shaped 15 trough for receiving the coil as the same is formed on the spindle 30. The members 64 and 66 are mounted in association with one another as described by means of the springs or flexible straps 68 and 70. These straps 68 and 70 are secured 20 to the frame member 69 and thus provide a substantially rigid mounting for abutment member 64 permitting downward movement of member 66 in respect to member 64 and into the dotted line position as represented at 72 in Figure 25 4 of the drawings. This movement takes place about rod or shaft 74, to which member 66 is connected by the ears 76 and 78, through the lever 80 which is operated by the link 82 having one of its ends connected to the lever 80 and its 30 other end connected to the movable core 84 of the solenoid 86. The operation and control of this solenoid 86 for moving the member 66 will be set forth hereinafter more in detail.

It will be noted that movement of member 66 35 into its dotted line position as shown in Figure 4 of the drawings provides an opening between members 66 and 64 permitting the discharge of the coil 62 from the trough formed by these members. In order to assure the proper discharge of the coil 62, one or more members such as 88 may 40 be connected to the shaft or rod 74 and adjusted in such a position that upon movement of member 66 this member 88 will contact the coil and dislodge the same if caught for its proper discharge from the trough.

The operation of the control circuit, which is 45 to be described hereinafter, is initiated by a switch 90 adjustably mounted upon a rod 92 as at 94, the rod 92 being secured to the bracket 65 in substantially parallel relation with the rod 74. This switch member comprises the contact 96 which is grounded in relation to the machine, and a spring contact 98 which is disposed in the control circuit by lead 100, this spring contact 50 98 being disposed in the path of the coil 62. As the coil 62 approaches the desired length, it engages and presses against the spring contact member 98 to raise the same into contacting relation with contact 96, closing the control circuit 55 for initiating certain operations.

The present invention also comprehends suitable means for cutting the coil after it has been formed to the desired length. Such means includes a lever 102 pivotally mounted as at 104 60 on the front face of the wall 6 and having a cutting blade 106 mounted adjacent one end thereof, the other end being connected through the rod mechanism 108 to the movable core 110 of the solenoid 112 also mounted conveniently in any 65 desired manner at the front of the coiling machine, this solenoid being in the control circuit for operating the lever 102 in its proper sequence of operations. Upon upward movement of the lever 102, the end adjacent the solenoid 112 70 through the lug 114 contacts the crank arm 116

of a switch 118, which switch, as will be herein-after more fully disclosed, completes a circuit for the operation of the solenoid 86. In order to amply support the spindle 30 upon downward movement of the knife blade 106 to cut the coil 5 formed by the machine, a support 120 is provided which has a V-shaped notch 122 in its upper end adapted to receive the spindle 30 and support it, the lower end of this support 120 being connected to the front wall 6 of the machine in any desired 10 manner.

As before stated, solenoids 56, 86 and 112 are disposed in a control circuit, this control circuit being diagrammatically shown in Figure 6 of the drawings. Operation of the solenoids effects certain operations in the coil forming machine. As pointed out, solenoid 56, when energized, causes gripping action between the cooperating feed rolls for the wire whereby the wire is fed to the spindle 30. Solenoid 112, when energized, moves 20 the lever 102 whereby the knife blade 106 is moved down into engagement with the coil to sever the same from the remaining portions of the wire. Furthermore, upon upward movement of lever 102, lug 114 operates switch 118 to energize 25 solenoid 86 whereby member 66 is moved to discharge the cut length of coil from the receiving means therefor. This cycle of operation is continuous so that the machine is entirely automatic, requiring no manual manipulation after 30 the switch is thrown to energize the control circuit.

The control circuit comprises a switch 126 for 35 including the same in circuit with the power lines 128 and 130. When the switch is thrown, a circuit is established through the lead 132 to contact 134, contact 136, through leads 138 and 140, through a relay 142, and then through the lead 144, contacts 146 and 148 of the control relay 150, then through contact 152 of this control 40 relay and through the lead 154. The completion of this circuit closes the time delay relay 142 and establishes another circuit through lead 132, contacts 134 and 136, lead 138 and lead 156 to the solenoid 56, and then through lead 158 through 45 the contacts 160 and 162 of the relay 142, and thence through lead 164 and lead 166 through contact 152 and lead 154, thereby energizing the solenoid 56 which immediately effects downward movement of the lever 50 about pivot point 52 50 to apply pressure moving rolls 14 and 18 into wire gripping engagement to feed wire to the coil forming means.

At this point it should be noted that a transformer 168 is energized at all times when the 55 switch 126 is thrown in, inasmuch as the high side 170 thereof is connected to contacts 134 and 152 on the 220 volt lines 132 and 154, the low side 172 thereof being connected through lead 176 and through lead 174 which includes switch 90 60 to coil 151 of the control relay 150.

After the solenoid 56 has been energized to cause feeding of the wire, the coil continues to be formed by the coil forming means until the end of the coil engages contact 98 of switch 90 65 which moves this contact into engagement with contact 96. This completes a circuit from the low side of the transformer through the lead 174, the switch 90, through the main control relay coil 151 and through the lead 176. This 70 energizing of the coil 151 causes the main control relay to close, thus opening contacts 146 and 148, and to close contacts 152 and 153 thereof. This movement of the main control relay causes the relay 142 to open, which in turn breaks the 75

circuit in which solenoid 56 is placed, as above described, to relieve pressure on the rolls 14 and 18 so that the wire feeding means is inoperative.

The closing of contacts 152 and 153 of the control relay, upon energization of coil 151, completes a circuit from lead 132 through contacts 134 and 136, through lead 118, through the solenoid 112 and to lead 180, to contact 153 through the control relay to contact 152 and thence 10 through lead 154. Energization of the solenoid 112 moves the lever 102 about pivot point 104 to bring the knife blade 106 into cutting relation with the wire and to sever a portion of the coil at that point. Upward movement of 15 lever 102 through the lug 114 causes a closing of switch 118 which completes a circuit from lead 132, contact 134, lead 182, through switch 118, solenoid 86, leads 184 and 166, contact 152, through lead 154. Energization of solenoid 86 20 causes a movement of link 82 to rotate lever 80, thus moving rod 74 and member 66 to discharge the coil from the coil receiving means.

After the coil has fallen through the opening between members 64 and 66, pressure is relieved 25 from contact 98 of switch 90 which opens, thus breaking the circuit including the coil 151 of the main control relay 150, thus breaking the circuit through contacts 152 and 153 whereby the lever 102 is returned to its initial position and the 30 circuit of the relay 142 is completed through contacts 146 and 148. Movement of lever 102 to its initial position opens switch 118 to deenergize the circuit including solenoid 86 whereby the member 66 is returned to its initial position forming 35 the V-shaped trough with member 64. The closing of the circuit of the relay 142 through contacts 146 and 148 energizes the relay 142 so as to complete a circuit through the contacts 160 and 162 thereof, which causes deenergizing of 40 solenoid 56, thus placing the control circuit in condition for another complete cycle of operations.

The main control relay may be wound with wire of large diameter, as is well understood, so 45 that there is a time delay between the opening of contacts 146 and 148 and the closing of contacts 152 and 153. This assures a complete deenergization of the wire feeding circuit before energization of the wire cutting circuit so that 50 the coil of wire is stationary at the time the cutter blade contacts the same. Any suitable means may be used in association with the main control relay to effect this time delay of any desired amount.

55 It is also to be noted that the length of coil being formed by the machine may be varied as desired by adjusting switch 90 through the means 94.

While I have herein described and upon the 60 drawings shown an illustrative embodiment of the invention, it is to be understood that the invention is not limited thereto but may comprehend other constructions, arrangements of parts, details and features without departing from the 65 spirit of the invention.

I claim:

1. In a wire coiling machine, the combination 70 of means for forming a coil from wire fed into said machine, means for cutting lengths of coil formed by said means, coil receiving means including a movable member, an electrical circuit for control of the operation of said means for forming lengths of coil, and an electrical circuit including electrical means for moving said member for discharging said coil from said machine.

2. In a wire coiling machine, the combination of means for forming a coil from wire fed into said machine, means for cutting lengths of coil formed by said means, coil receiving means including a movable member, an electrical circuit 5 for control of the operation of said means for forming lengths of coil, and an electrical circuit including electrical means for moving said member for discharging said coil from said machine, said circuit including means controlled by said 10 coil for controlling said first-named circuit.

3. In a wire coiling machine, the combination of means for forming a coil from wire fed into said machine, means for cutting lengths of coil formed by said means, coil receiving means including a movable member, means controlled by 15 said coil for operating said cutting means, and electrically operated means operated after a predetermined movement of said cutting means for moving said member to discharge said cut coil 20 from said machine.

4. In a wire coiling machine, the combination of power means, wire feeding means driven thereby, means for forming a coil from said wire, means for cutting lengths of coil formed by said 25 means, means for controlling the operation of said wire feeding means, means for controlling operation of said coil cutting means, and means for controlling the operation of said last two mentioned means, said means including means 30 whereby said cutting means is operated only after a delayed interval after said feeding means is inoperative.

5. In a wire coiling machine, the combination of power means, wire feeding means driven 35 thereby, means for forming a coil from said wire, means for cutting lengths of coil formed by said means, a control circuit including means for controlling the operation of said wire feeding means and means for controlling operation of said coil 40 cutting means, and means in said circuit and controlled by said coil for controlling the operation of said last two mentioned means, said control circuit including means whereby said cutting means is operated only after a delayed interval 45 after said feeding means is inoperative.

6. In an automatic wire coiling machine, the combination of power means, wire feeding means driven thereby, means for forming a coil from 50 said wire, means for cutting lengths of coil formed by said means, a coil receiving means having discharge means associated therewith, and a control circuit having means for controlling automatically the feeding of said wire and the forming, cutting and discharging of said coil. 55

7. In an automatic wire coiling machine, the combination of power means, wire feeding means driven thereby, means for forming a coil from said wire, means for cutting lengths of coil formed by said means, a coil receiving means having discharge means associated therewith, a control circuit having means for controlling automatically the feeding of said wire and the forming, cutting and discharging of said coil, and means in said circuit and controlled by said coil 60 fater a predetermined length has been formed 65 for initiating said sequence of operations.

8. In an automatic wire coiling machine, the combination of power means, wire feeding means driven thereby, means for forming a coil from 70 said wire, means for cutting lengths of coil formed by said means, a coil receiving means having discharge means associated therewith, a control circuit having means for controlling automatically the feeding of said wire and the form- 75

- ing, cutting and discharging of said coil, means in said circuit and controlled by said coil after a predetermined length has been formed for initiating said sequence of operations, and means 5 in said circuit whereby said cutting means is operated only after a delayed interval after said feeding means is inoperative.
9. In a wire coiling machine, the combination of power means, wire feeding means operated thereby, wire coiling means, means for cutting lengths of coil formed by said last-named means, an electrical circuit for controlling the operation of said wire feeding and wire cutting means, said circuit including a control switch, a solenoid for 10 controlling said wire feeding means, a solenoid for controlling said wire cutting means, a control relay in said circuit normally disposed to complete a circuit through said wire feeding control solenoid upon closing of said switch, and means 15 operated by said wire coil for completing a circuit for operating said control relay to deenergize said wire feeding circuit and to energize a circuit including said solenoid for operating said wire cutting means.
10. In a wire coiling machine, the combination of power means, wire feeding means operated thereby, wire coiling means, means for cutting lengths of coil formed by said last-named means, an electrical circuit for controlling the operation 20 of said wire feeding and wire cutting means, said circuit including a control switch, a solenoid for controlling said wire feeding means, a solenoid for controlling said wire cutting means, a control relay in said circuit normally disposed to complete a circuit through said wire feeding control solenoid upon 25 closing of said switch, means operated by said wire coil for completing a circuit for operating said control relay to deenergize said wire feeding circuit and to energize a circuit including said solenoid for operating said wire cutting means, means operated in accordance with the operation 30 of said wire cutting means to operate said solenoid for said coil discharging means, said control relay having means to cause a time delay between the complete deenergization of said solenoid for 35 said wire feeding means and the completion of said circuit through said control relay and said solenoid for said wire cutting means.
11. In a wire coiling machine, the combination of power means, wire feeding means operated thereby, wire coiling means, means for cutting lengths of coil formed by said last-named means, means for receiving and discharging said cut lengths of coil, an electrical circuit for controlling the operation of said wire feeding, wire cutting and discharge means, said circuit including 40 a control switch, a solenoid for controlling said wire feeding means, a solenoid for controlling said wire cutting means, a solenoid for controlling said coil discharging means, a control relay in said circuit normally disposed to complete a circuit 45 through said wire feeding control solenoid upon closing of said switch, means operated by said wire coil for completing a circuit for operating said control relay to deenergize said wire feeding circuit and to energize a circuit including said solenoid for operating said wire cutting means, means operated by said wire cutting means to 50 complete a circuit including said solenoid for said coil discharging means, said control relay having means to cause a time delay between the complete deenergization of said solenoid for said wire feeding means and the completion of said circuit through said control relay and said solenoid for 55 said wire cutting means.
12. In a wire coiling machine, the combination of power means, wire feeding means operated thereby, wire coiling means, means for cutting lengths of coil formed by said last-named means, means for receiving and discharging said cut lengths of coil, an electrical circuit for controlling the operation of said wire feeding, wire cutting 60 means, and means operated in accordance with the operation of said wire cutting means to operate said solenoid for said coil discharging means.
13. In a wire coiling machine, the combination of power means, wire feeding means operated thereby, wire coiling means, means for cutting lengths of coil formed by said last-named means, means for receiving and discharging said cut 65 lengths of coil, an electrical circuit for controlling the operation of said wire feeding, wire cutting and discharge means, said circuit including a control switch, a solenoid for controlling said wire feeding means, a solenoid for controlling said wire cutting means, a solenoid for controlling said coil discharging means, a control relay in said circuit normally disposed to complete a circuit through said wire feeding control solenoid upon closing of said switch, means operated by said wire coil for completing a circuit for operating said control relay to deenergize said wire feeding circuit and to energize a circuit including said solenoid for operating said wire cutting means, means operated in accordance with the operation 70 of said wire cutting means to operate said solenoid for said coil discharging means, said control relay having means to cause a time delay between the complete deenergization of said solenoid for said wire feeding means and the completion of said circuit through said control relay and said solenoid for said wire cutting means.
14. In a wire coiling machine, the combination of power means, wire feeding means operated thereby, wire coiling means, means for cutting lengths of coil formed by said last-named means, means for receiving and discharging said cut lengths of coil, an electrical circuit for controlling the operation of said wire feeding, wire cutting and discharge means, said circuit including a control switch, a solenoid for controlling said wire feeding means, a solenoid for controlling said wire cutting means, a solenoid for controlling said coil discharging means, a control relay in said circuit normally disposed to complete a circuit through said wire feeding control solenoid upon closing of said switch, means operated by said wire coil for completing a circuit for operating said control relay to deenergize said wire feeding circuit and to energize a circuit including said solenoid for operating said wire cutting means, means operated by said wire cutting means to complete a circuit including said solenoid for said coil discharging means, said control relay having means to cause a time delay between the complete deenergization of said solenoid for said wire feeding means and the completion of said circuit through said control relay and said solenoid for said wire cutting means.
15. In a wire coiling machine, the combination of power means, wire feeding means operated thereby, wire coiling means, means for cutting lengths of coil formed by said last-named means, an electrical circuit for controlling the operation of said wire feeding and wire cutting means, said 75

circuit including a control switch, electrically operated means for controlling said wire feeding means, electrically operated means for controlling said wire cutting means, electrical control means 5 in said circuit normally disposed to complete a circuit through said wire feeding control means upon closing of said switch, and means operated by said wire coil for completing a circuit for operating said electrical control means to deener- 10 gize said wire feeding circuit and to energize a circuit including said electrically operated means for operating said wire cutting means.

16. In a wire coiling machine, the combination of power means, wire feeding means operated 15 thereby, wire coiling means, means for cutting lengths of coil formed by said last-named means, an electrical circuit for controlling the operation of said wire feeding and wire cutting means, said circuit including a control switch, electrically 20 operated means for controlling said wire feeding means, electrically operated means for controlling said wire cutting means, electrical control means in said circuit normally disposed to complete a circuit through said wire feeding control 25 means upon closing of said switch, means operated by said wire coil for completing a circuit for operating said electrical control means to deener- gize said wire feeding circuit and to energize a circuit including said electrically operated means 30 for operating said wire cutting means, said electrical control means having means to cause a time delay between the complete deenergization of said circuit for said wire feeding means and the completion of said circuit through said elec- 35 trical control means and the electrically operated means for said wire cutting means.

17. In a wire coiling machine, the combination of power means, wire feeding means operated thereby, wire coiling means, means for cutting 40 lengths of coil formed by said last-named means, means for receiving and discharging said cut lengths of coil, an electrical circuit for controlling the operation of said wire feeding, wire cutting and discharge means, said circuit including a 45 control switch, electrically operated means for controlling said wire feeding means, electrically operated means for controlling said wire cutting means, electrically operated means for controlling said coil discharging means, electrical control means in said circuit normally disposed to complete a circuit through said electrically operated 50 means for said wire feeding means upon closing of said switch, means operated by said wire coil for completing a circuit for operating said electrical control means to deenergize said wire feeding circuit and to energize a circuit including said electrically operated means for said wire cutting means to operate the same, and means operated in accordance with the operation of said wire cutting means to complete a circuit including said electrically operated means for said coil discharging means for operation thereof.

18. In a wire coiling machine, the combination of power means, wire feeding means operated 65 thereby, wire coiling means, means for cutting lengths of coil formed by said last-named means, means for receiving and discharging said cut lengths of coil, an electrical circuit for controlling the operation of said wire feeding, wire cutting and discharging means, said circuit including a 70 control switch, electrically operated means for controlling said wire feeding means, electrically operated means for controlling said wire cutting means, electrically operated means for control-

ling said coil discharging means, electrical control means in said circuit normally disposed to complete a circuit through said electrically operated means for said wire feeding means upon closing of said switch, means operated by said wire coil 5 for completing a circuit for operating said electrical control means to deenergize said wire feeding circuit and to energize a circuit including said electrically operated means for said wire cutting means to operate the same, means operated in accordance with the operation of said wire cutting means to complete a circuit including said electrically operated means for said coil discharging means for operation thereof, said electrical control means having means to cause 10 a time delay between the complete deenergization of said circuit for said wire feeding means and the completion of said circuit through said electrical control means and the electrically operated means for said wire cutting means. 15

19. In a wire coiling machine, the combination of a frame, means mounted on said frame for forming a coil from wire fed into said machine and discharging the same substantially normal to said frame, and a coil receiving means pivot- 20 ally mounted with respect to said frame and movable into and out of cooperative relation with said coil forming means. 25

20. In a wire coiling machine, the combination of a coil receiving means, said means having a 30 movable member for discharge of lengths of coil from said means, and means movable with said movable member and spaced in relation thereto and adapted to engage with said lengths of coil to dislodge the same from said means to assure 35 discharge of said lengths of coil from said receiving means.

21. In a wire coiling machine, the combination of means for forming a coil from wire fed into said machine, means for cutting lengths of coil from said means including a cutter, means for moving said cutter, a coil receiving means including a rotatable shaft, said means comprising cooperating members one of which is mounted on said shaft for movement with respect to the 40 other for discharge of said lengths of coil from said receiving means, and an electrical circuit controlled by said cutter and including means for 45 rotating said shaft.

22. In a wire coiling machine, the combination of means for forming a coil from wire fed into said machine, means for cutting lengths of coil from said means including a cutter, an electric circuit including means for moving said cutter, a coil receiving means including a rotatable shaft, 50 said means comprising cooperating members one of which is mounted on said shaft for movement with respect to the other for discharge of said lengths of coil from said receiving means, and an electrical circuit controlled by said cutter and including means for rotating said shaft. 55

23. In a wire coiling machine, the combination of means for forming a coil from wire fed into said machine, means for cutting lengths of coil from said means including a cutter, means for moving said cutter, a coil receiving means including a rotatable shaft, said means comprising cooperating members one of which is mounted on said shaft for movement with respect to the other for discharge of said lengths of coil from said receiving means, and an electrical circuit having a 65 switch operated by said cutter for control thereof and including means for rotating said shaft. 70

ALBERT M. OLGAY.
